UNITED STATES PATENT OFFICE.

PHILIP McGINNIS, OF LONDON, CANADA.

WINDOW.

No. 821,665.

Specification of Letters Patent.

Patented May 29, 1906.

Application filed July 30, 1904. Serial No. 218,860.

To all whom it may concern:

Be it known that I, PHILIP McGINNIS, a subject of the King of Great Britain, and a resident of London, in the Province of Ontario and Dominion of Canada, have invented 5 new and useful Improvements in Windows, of which the following is a full, clear, and exact specification.

My invention relates to windows of the ordinary type consisting of two framed vertically-movable glass plates and which are adapted, in addition to being moved up and down, to have a lateral movement, so that they may be swung inwardly, the object of 15 the invention being to provide simple and effective means whereby the result above stated may be achieved.

In the drawings, Figure 1 illustrates a front view of the window as seen from the interior of the house. Fig. 2 represents a horizontal section through the same when the windows are swung open. Fig. 3 is a side elevation with parts in section. Fig. 4 represents a front-view section illustrating the hinge on which the window is swung, and Fig. 5 represents a horizontal section on line 20 5 5 of Fig. 4. Fig. 6 is a sectional plan on line 6 6 of Fig. 3 of the mechanism for connecting the stop with the window-frame, and Fig. 7 is a section through the same along line 25 7 7 of Fig. 6. Fig. 8 is a detailed front view of the plate fixed to the frame of the window shown in Figs. 6 and 7, and Fig. 9 is a front view of the plate fastened to the stop shown 30 in Figs. 6 and 7.

In the drawings, A represents the frame of the window constructed in the usual fashion, consisting in part of the boxes B, adapted to contain the weights C, which counterbalance 35 the weight of the windows.

D represents the stool and sill of the window.

F represents the sash of the window-glass G, which is constructed in the usual manner, 40 being provided at both ends with a groove containing cords H, connected to the weights. The cords are generally hooked to pins I, located in recesses, as shown in Fig. 2, in which, however, the hook is shown free.

50 The parts J and J' are the two exterior stops, against which the upper of the two sashes is adapted to bear in the normal position to prevent its falling out.

K is the intermediate stop at the left hand 55 of the window, and K' its corresponding construction at the right hand of the window.

The two interior stops of the inner sash are shown as composed of two pieces each, the upper pieces L and L' being permanently screwed to the frame A and the two lower 60 pieces contiguous, respectively, to L and L' are shown as M and N.

M is represented as hinged to the frame A, as shown in Fig. 2, so as to allow it to swing inwardly into the room when desired. N, the 65 opposite stop, is shown as entirely removable from the window. It adjoins the upper portion of the stop L' at the angular cut O, inclined both laterally and from front to rear, and is fastened to the frame A by means of 70 the mechanism shown in detail in Figs. 6, 7, 8, and 9. This mechanism consists of the plate P, having the appearance of an inverted keyhole and provided with an edge flange P', which rests in a cut-out portion A' in the 75 frame A, so as to allow the head of the screw Q to project therethrough and to move vertically therein. This screw Q passes through the oscillating bearing R, through an opening in the stop N, and is connected at the outside 80 with a handpiece S, larger than the opening through which the screw projects in the stop N.

The sashes F of the windows are each provided at one side with two ordinary aligned screws T, the heads of which project from the 85 windows a short distance. These screws are adapted to be engaged by the double hinges U V. (Shown in detail in Figs. 4 and 5.) A metallic box W is countersunk in the stop M, and at the bottom of this box, transversely 90 therethrough, is pivoted the lower portion V of the double hinge in such a manner as to permit this hinge to be moved vertically in and out of the box W. To the lower arm V of the hinge is pivotally connected the upper 95 arm U, which is adapted to have a horizontal movement and which is provided with a beveled cut X, adapted to receive the screws T on the window. To prevent accidental disengagement, I pivot a latch Y to the hinge-arm U, the latch normally projecting into the cut X, and thus into the path of the screws T. This latch Y is weighted and will swing aside automatically when the screw T comes down upon the hinge-arm U, swinging 100 back to its normal position, as shown in Fig. 4, so as to prevent any upward movement of the sash unless the latch is first swung aside by hand. Similar boxes W, with hinges U V 105 therein, are also arranged on the parting-strip K to coöperate with the screws T of the upper sash.

At the right-hand side of the frame A there is provided a hook or projection Z, to which the temporarily-disconnected window-cord may be attached when the window is opened inwardly.

In the normal condition of the window with all the stops in place the window has the appearance shown in Fig. 1, except that the two double hinges U V are thrown back 10 into their pockets or boxes W, so that they do not project from the stop M, as shown in dotted lines in Fig. 4. When the window is in that condition, the screws T of the upper sash can readily pass the lower sash as the two are moved vertically with regard to each other, and the window operates in all respects exactly like the ordinary window of this character, being connected to the counterweights in the usual fashion. When, however, it is designed to clean the windows with safety or to open them inwardly for any reason whatsoever, the operator proceeds as follows: The lower sash is raised slightly above the position shown in Fig. 1. The two double 20 hinges U V are pulled down from their boxes or containers into the position shown in Fig. 1 and the sash lowered till the studs T rest in the notches X, as shown in Fig. 1. The handpiece S at the opposite side of the window is raised, and consequently the screw-head Q passes from behind the narrow portion of the keyhole in alignment with the larger portion thereof, and there is consequently no remaining connection between 30 the stop N and the frame A. The operator exerts a slight inward and upward pull on the handpiece S, and the stop N is removed from the side of the window altogether. Nothing now prevents the sash from being 40 swung inwardly. The sash is turned toward the person in the interior of the room. The sash-cord H is unhooked from I and hooked into Z, leaving the sash without any connection at the right-hand side and free to swing 50 inwardly. Under ordinary circumstances sufficient inward swing is obtained when the stop M is rigidly connected to the frame A. In such case, of course, the parts L and M would form one single continuous piece, differing in no respect from the parts now in ordinary use. If a greater swing is desired, the hinges shown attached to M in Fig. 2 may be provided, and these hinges allow the lower sash to swing entirely within the room without any limit other than the walls of the 55 room.

Having opened the lower sash to the position shown in Fig. 2, if it is now desired to open the upper sash inwardly the operator 60 may remove the intermediate stop K' by simply taking it out of its recess after this sash has been lowered until the screws T rest in the hinge-arm U, located on the stop K. In the ordinary construction of windows 65 this intermediate stop is not nailed to the

frame A, but is merely inserted in a recess in A and held therein with sufficient rigidity by reason of its being embraced partially on its three vertical sides by the walls of the recess and on the fourth vertical side by two projecting lips of the meeting-rails situated on the lower rail of the upper sash and the upper rail of the lower sash, respectively. Consequently the removal of this particular stop K' is an ordinary feature of the window now 70 universally used. In the window of my invention I divide this stop into two pieces, similar to the device of the right-hand stop L' N, except that instead of making the cut O angular I make a horizontal cut or a cut slightly 75 inclined toward the left and place the lower part of the stop K' on the pin D' in the sill D, as shown in Fig. 3. To remove this stop K', it is consequently only necessary to pull the stop out of the recess in the frame A. The 80 corresponding stop K at the left-hand side of the window is also provided with two double hinges of the same construction as shown in Figs. 3 and 4, and when these two hinges located in K are thrown outwardly and the upper sash lowered until the two screws T rest in the two hinges the stop K' is pulled out, as described, the sash-cord disconnected from the hook I and hooked into the projection Z, and the upper sash will swing into the room, 85 so that it may be cleaned or repaired with safety. If it is now desired to return the window to its normal condition, the upper sash is swung back until its free edge approaches the frame A, when its sash-cord is disconnected from the projection Z and hooked into the inverted hook I. The window is then 90 completely swung back into its normal position—that is, until it is parallel and contiguous with the inner faces of the two outside stops J J'. The stop K' is then returned to its place by placing it on the pin D', as shown in Fig. 3, and pushing it back into its groove, and the 95 window is thereupon raised to the position shown in Fig. 1, which represents the normal closed condition of the upper window. It will be apparent that by this upward motion the screws T have become disconnected from the double hinge U V, and these two double 100 hinges are thereupon folded into their boxes W either by contact with the lip of the meeting-rail or by hand, and the upper sash is in its normal condition. Thereafter if the lower sash is to be closed it is first reengaged with the sash-cord and its swinging end pushed toward the frame until the outside edges of the sash F are parallel to and contiguous with the inner faces of the intermediate stops K K'. The stop N is now put into place by inserting 105 its upper acute angle into the corresponding space at O and pushing its lower end toward the frame until it assumes the position shown in Fig. 1, the handpiece S remaining raised during the operation. When this stop N is 110 in place, as shown in Fig. 1, the hand-piece S 115

is lowered, causing the screw-head Q to project beyond the narrow part of the keyhole in P, assuming the position shown in Fig. 7 and firmly locking the stop N to the frame A. 5 The lower sash is now raised a short distance until its screws T become disengaged from the double hinges U V, which are thrown into their boxes W, as indicated in dotted lines in Fig. 4, where they remain out of sight. The 10 sash has now been restored to its original position and except for the four projecting screws T and the handpiece S there is nothing to indicate to a person in the interior of the room that the window differs in construction 15 from any ordinary window now in general use. These four screws and the handpiece S are so small, however, as hardly to be noticeable, and they are usually covered by curtains.

20 If it is desired to secure the catch P Q R S in its locking position at this point, or in its upper or unlocked position while it is removed from the window, a slight rotating motion is given to the handpiece S, which 25 forces it into frictional contact with the inner wall of N and retains it in that or any other desired position.

It will be seen that the improvement herein described is of an exceedingly simple and 30 efficacious character. All of its parts, so far as the woodwork is concerned, are the same parts now in use, which will permit any ordinary window to be altered at the smallest possible expense, so that it can contain the 35 improvement of my invention. The only changes in the woodwork consists in removing parts therefrom for the reception of the double hinges and the other devices; but in no place is it necessary to make a special 40 wooden part in the construction of this window. Consequently any architect or window-framer by simply acquiring the necessary metallic parts can provide a house with the improvement of my invention. The 45 screws T and the other screws used in connecting parts can be bought at any hardware-store. The double hinge U V with its box W in order to be attached to the stop M or K require merely the gouging out of the recesses in these stops in order to be properly fitted. An ordinary auger or chisel may be used in providing the necessary recesses for the reception of the locking device P Q R S of the stop N. 50

Of course many of the parts which I have described may be replaced by others having corresponding functions; but the main idea which I have had in mind in devising the present improvement has been to produce a window of the character described without 55 requiring the use or employment of special hand-made parts or of altering the construction of the window now in common use to any appreciable extent except by the addition of such necessary metal parts as are required to provide a disappearing hinge and a removable stop at the opposite side of the window-frame. 60

65

What I claim as my invention, and desire to secure by Letters Patent, is— 70

1. The combination of the frame, the sliding sash provided with a projection, a hinge carried by said frame and adapted to swing about an axis parallel with the direction in which the sash moves, said hinge having a 75 seat for said projection, and a latch carried by said hinge, to lock the projection to the hinge.
2. The combination with the frame and the sliding sash, of a double hinge adapted to 80 connect with the sash in a predetermined position thereof, said hinge comprising a section pivoted to the frame about an axis transverse to the direction in which the sash slides, and another slotted section adapted to engage a rigid projection on the sash and permanently carried by and pivoted to the first-named section about an axis parallel with the path in which the sash slides. 85

85

In testimony whereof I have hereunto set 90 my hand in the presence of two subscribing witnesses.

PHILIP McGINNIS.
